GUARD RAIL FASTENER

Thomas Maney, Louisville, Ky.

Application September 14, 1931
Serial No. 562,779

19 Claims. (Cl. 238—20)

This invention relates to an improvement in guard rail fasteners, in which a chair for the guard rail is seated on a tie plate and supports the guard rail. Under certain circumstances, it is desirable to fasten the chair directly to the plate and to use the weight of the rolling load as a holding down agent through the medium of the plate rather than the rail.

In my former Patent Numbers 1,638,739, of 10 August 9, 1927; 1,639,524, of August 16, 1927; and 1,713,878, of May 21, 1929, the guard rails were shown as fixed to the chairs, and the latter were provided with means for underlying a portion of the main rail in order to hold them down 15 on the tie plate in position to support the guard rail. At the same time, the chairs were separable from the guard rail and tie plate, which is desirable to facilitate installation or the removal of parts.

20 In my present invention, this separable relation between tie plate, guard rail and chair is retained, but provision is made for securing the chair directly to the tie plate by separable fasteners, which permit ready removal of the chair 25 or guard rail and which makes use of the weight of the rolling load through the medium of the main rail and tie plate to hold the chair and guard rail securely down in proper positions.

Another feature of my present invention is 30 the adjustability of the chair, wherein it may be moved inward or tilted, or both, by the use of lateral and vertical shims at the rear of the chair, and arms carried by the chair serve to prevent a complete overturning of the main rail but allow 35 the main rail to cant within safe limits.

In the accompanying drawings:

Fig. 1 is a side elevation of my invention showing the main and guard rails in dotted lines;

Fig. 2 is a top plan view thereof;

40 Fig. 3 is an end elevation of the tie plate and chair taken from the left-hand side of Fig. 1;

Fig. 4 is a similar view taken from the right-hand side of Fig. 1;

Fig. 5 is a detached perspective view of a nut 45 lock; and

Figs. 6 and 7, 8 and 9, 10 and 11 are, respectively, detail plan and sectional views of the outer sides of the chair and plate, showing various adjustments of the chair by means of shims.

50 The tie plate 1 is of the usual construction, provided with an upturned shoulder 2 at one extreme end and with a shoulder 3 spaced inward from the opposite end in position to receive an edge of the base flange of the main rail 4, which 55 is seated on the tie plate 1.

The usual openings 5 are provided to receive spikes for securing the tie plate to the tie.

The chair is designated as a whole by the numeral 6 and is provided with a base portion 7, from which an upstanding arm 8 extends, upwardly and inwardly, and is provided with lateral flanges 9 to fit under and engage the head of the guard rail 10, and which guard rail is held in place by a clip 10'. A seat 11 is formed in the chair 6 to receive the base of the guard rail and support the same. The forward edge of the base 7 is provided with notches 12 therein to receive bolts 13, the lower end portions of which have flattened sides 14 extending through elliptical slots 15 formed in the tie plate 1 to prevent the 60 bolts from turning in these slots. Heads 16 on the lower ends of the bolts engage under the bottom of the tie plate. The bolts 13 are thus upstanding from the tie plate 1 and receive the 65 notches 12 in the base 7 of the chair, and the upper ends of these bolts 13 have nuts 17 screwed thereon, which nuts are, however, substantially elongated to permit ready connection with a wrench. Washers 18 are interposed between the 70 undersides of the nuts 17 and the upper surface 80 of the base 7 of the chair, and as shown in Figs. 1 and 2, these washers overhang the edge of the base flange of the main rail 4 so as to permit a slight cant of the main rail but preventing a complete overturn thereof. The slots 15 for the bolts 85 13 are approximately at an edge of the main rail base flange.

After the tie plates and main rails have been applied and secured in place, the chair 6 is placed on the plate in the position shown in Fig. 1, 90 where it abuts against the upstanding shoulder 2 and the washers 18 are then applied to the bolts 13 and the nuts 17 screwed down into place. The 95 nuts are always accessible for turning, and after a limited period of service, sufficient to reduce any minor inequalities in the bearing surfaces, the nuts should be again tightened and locked in place by the insertion of locking strips 19 between the sides of the chair 6 and the nuts 17, said locking strips having angularly grooved faces 20 100 therein for receiving the corners of the nuts and holding the nuts against turning.

The washers 18 are of such size and position as to leave any desired distance between them and the upper side of the main rail base. This 105 prevents any ordinary movement of the main rail, except that of direct lateral pressure, from being transmitted to the chair and, at the same time, prevents the main rail from lifting on the inside beyond a fixed distance. Ordinarily, the main rail 110

would not move sufficiently to engage the washers 18, but in the event of faulty adjustment of the swinging wheels of the locomotive, causing the heads of the main rails to be crowded, this mounting 5 permits easement within safety limits, but would prevent a complete overturning of the main rail, thus offering both a means of easement and a factor of safety.

While the essential points of chair support on 10 the base are the areas designated generally by the arrows A, B and C, and while the principal wear will be against the side of the guard rail head at the upper end of the arm 8 and the flanges 9, due to the pressure of the guard rail there- 15 against by the wheel flanges, nevertheless some wear will take place at the point designated by the arrow D from pressure and movement of the rail base. As originally applied, the main rail base is spaced slightly from the chair base 7 at D, which 20 distance may be approximately one-sixteenth of an inch, but due to wear at this point, this distance will increase, and when it has increased to approximately one-eighth of an inch, the chair 25 6 may be bodily adjusted laterally, as shown in Figs. 6 and 7, by the insertion of the shim 21 be- 30 tween the back edge of the chair 6 and the up- standing shoulder 2 of the tie plate 1, the op- 35 posite ends of the shim 21 being bent forwardly about the sides of the chair 6 as shown at 22. As 40 wear increases, subsequent adjustments may be made by the use of other shims, as for instance shown at 23 in Figs. 8 and 9, which not only moves the chair inward toward the main rail but also 45 lifts the rear of the chair. Further lifting action 50 may be accomplished by the use of shims 24 and 25 in Figs. 10 and 11, which provides a consider- 55 able range of adjustment for the head of the guard rail by a method that is very inexpensive and simple.

The shims may be applied without the removal 40 of any parts and locked in place by bending the free ends, as shown. This method of adjustment causes an inward adjustment of the guard rail 45 head by tilting the chair about a point of contact with the plate at the front of the chair, as well as causing a desired inward shifting movement thereof.

I claim:

1. In a guard rail fastener, the combination of a tie plate, a chair for supporting a guard rail, and means for causing tilting movement of the chair relative to the tie plate to cause an inward adjustment of the guard rail head.

2. In a guard rail fastener, the combination of a tie plate, a chair mounted thereon for supporting a guard rail, and means for causing an inward tilting movement of the chair about the point of contact with the tie plate at the front of the chair for causing an inward adjustment of the guard rail head.

3. In a guard rail fastener, the combination of a tie plate, a chair mounted thereon, and a shim inserted between the chair and tie plate for causing an inward tilting movement of the chair and an adjustment of the guard rail.

4. In a guard rail fastener, the combination of a tie plate, a chair mounted thereon for supporting a guard rail, and a shim inserted under an edge of the chair for causing an inward tilting movement of said chair and an inward adjustment of the guard rail head.

5. In a guard rail fastener, the combination of a tie plate, a chair mounted thereon for supporting the guard rail, and a shim inserted under the outer edge of the chair between said chair

and the tie plate for causing an inward tilting movement of the chair about the point of contact of the chair with the tie plate at the front of the chair, for causing an inward adjustment of the guard rail head.

80

6. In a guard rail fastener, the combination of a tie plate, a guard rail chair mounted thereon, and a shim inserted between the tie plate and chair for causing an inward tilting movement of the chair.

85

7. In a guard rail fastener, the combination of a tie plate, a guard rail chair mounted thereon, and a flat shim inserted between the tie plate and chair for causing an inward shifting movement of the chair, said shim having the ends thereof bent laterally to prevent displacement.

90

8. In a guard rail fastener, the combination of a tie plate having an upturned flange, a chair supported on the plate, and a shim inserted be- 95 tween the flange and the chair for causing an inward shifting movement of the chair, and having laterally bent ends to prevent displacement thereof.

95

9. In a guard rail fastener, the combination of a tie plate for supporting a main rail, a chair mounted on the tie plate beside the main rail, and normally spaced slightly therefrom, said chair being adapted to receive a guard rail, and a flat shim of approximately uniform thickness throughout inserted between the outer portions of the tie plate and chair for causing an inward adjustment of the guard rail, said shim having laterally turned end portions to prevent displacement thereof.

100

10. In a guard rail fastener, the combination of a tie plate for receiving a main rail, a chair mounted on the tie plate beside the main rail, said chair being adapted to receive a guard rail, and means for causing a tilting of the chair relative to the tie plate for adjusting the position of the guard rail.

110

11. In a guard rail fastener, the combination of a tie plate for receiving a main rail, a chair mounted on the tie plate beside the main rail, and adapted to support a guard rail, and a shim for causing a tilting movement of the chair about its point of engagement with a tie plate at the front of the chair, for causing an inward adjustment of the guard rail.

120

12. In a guard rail fastener, the combination of a tie plate for receiving a main rail, and a guard rail chair supported on the tie plate beside the main rail and carrying a projection overlapping the main rail base flange, spaced above said base flange and normally free to contact with the main rail.

130

13. In a guard rail fastener, the combination of a tie plate for supporting a main rail for slight turning movements thereon, and a chair mounted on the tie plate beside the main rail and having spaced projections overlapping the main rail base in normally spaced relation therefrom to permit slight turning movement of the main rail and adapted to be engaged by said main rail base and limit said turning movement.

135

14. In a guard rail fastener, the combination of a tie plate adapted to support a main rail for slight turning movements thereon, a chair mounted on the tie plate beside the main rail, bolts for the chair, and one or more members secured to the chair by the bolts and overlapping the main rail base in normally spaced relation therefrom to permit slight turning movement of the main rail and adapted to be engaged by the main rail base and limit said turning movement.

140

145

15. In a guard rail fastener, the combination of a tie plate adapted to support a main rail for slight turning movements thereon, a chair mounted on the tie plate beside the main rail, 5 bolts for holding the chair in place, and washers attached to the bolts and projecting laterally from the chair overlapping the main rail base and spaced above said main rail base in position to contact therewith. 80
- 10 16. In a guard rail fastener, the combination of a tie plate, a main rail, a guard rail chair mounted on said tie plate, and fastening means for securing the chair directly to the tie plate, said means adjacent to and overlapping the main rail base. 85
- 15 17. In a guard rail fastener, the combination of a tie plate, a main rail, a guard rail chair mounted on said tie plate, and bolts connected with the tie plate and chair securing the chair 20 directly to the tie plate, and means on the bolts overlapping the main rail base. 90

- 75
18. In a guard rail fastener, the combination of a tie plate having slots therein, a guard rail chair mounted on the tie plate, and bolts having end portions thereof mounted in the slots and constructed to prevent turning therein, and nuts on the opposite end portions of the bolts and bearing on portions of the chair to secure the chair directly to the tie plate. 95
19. In a guard rail fastener, the combination of a tie plate, a guard rail chair mounted thereon and having a notch therein, a bolt secured to the tie plate and extending through the notch in the chair, a nut for holding the chair in place, and a washer interposed between the nut and chair and having an overhang on the inner side of the chair in position to prevent overturning of the main rail supported by the tie plate beside the chair. 100
